(57) **CLAIM**

The ornamental design for a cat wall shelving set, as shown and described.

DESCRIPTION

FIG. 1 is a top perspective view of the first component of a cat wall shelving set of FIG. 25, according to my new design, shown separately to reveal all aspects of the design; FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a front perspective view of the second component of the cat wall shelving set of FIG. 25, shown separately to reveal all aspects of the design;

FIG. 10 is a rear perspective view thereof;

FIG. 11 is a front view thereof;

FIG. 12 is a rear view thereof;

FIG. 13 is a left side view hereof;

FIG. 14 is a right side view hereof;

FIG. 15 is a top view hereof;

FIG. 16 is a bottom view thereof;

FIG. 17 is a top perspective view of the third component of the cat wall shelving set of FIG. 25, shown separately to reveal all aspects of the design;

FIG. 18 is a bottom perspective view thereof;

FIG. 19 is a front view thereof;

FIG. 20 is a rear view thereof;

FIG. 21 is a left side view thereof;

FIG. 22 is a right side view thereof;

FIG. 23 is a top view thereof;

FIG. 24 is a bottom view thereof; and,

(Continued)

FIG. 25 shows perspective views of the three components of the cat wall shelving set combined. The broken lines in the drawings illustrate the portions of the cat wall shelving set, which form no part of the claimed design.
